DEVICE FOR CLEANING A PLURALITY OF CLOSELY ADJACENT THIN PLATES OR SIMILAR OBJECTS

William R. Wright, Warren, Mass.

Application November 15, 1952, Serial No. 320,719

3 Claims. (Cl. 15—210)

This invention relates to a device for cleaning dust or dirt from a plurality of closely adjacent and relatively thin objects, such as a series of thin plates, blades or discs, and for lubricating such parts when desired.

It is the general object of the invention to provide for easy and rapid replenishment of the wiping material as it becomes worn or soiled.

A further object is to provide a device having convenient storage provisions for a supply of fresh wiping material. I also provide for increasing the tension on the cleaning material as it is drawn through the device.

To the accomplishment of these general objects, my invention further relates to arrangements and combinations of parts which will be hereinafter described and more particularly pointed out in the appended claims.

A preferred form of the invention is shown in the drawings, in which

Fig. 1 is a partial side elevation of my improved cleaning device;

Figs. 2 and 2a are partial side elevations similar to Fig. 1 but showing the parts in a different position;

Fig. 3 is a partial front elevation, looking in the direction of the arrow 3 in Fig. 1;

Fig. 4 is a fragmentary front elevation, looking in the direction of the arrow 4 in Fig. 1;

Fig. 5 is a detail sectional view, taken along the line 5—5 in Fig. 2;

Fig. 6 is an enlarged detail sectional view, taken along the line 6—6 in Fig. 2; and

Fig. 7 is a view similar to Fig. 6 but embodying the use of tubular cleaning material.

Referring to the drawings, my improved cleaning device comprises a handle portion 10 having a storage drum 12 secured to its lower end and adapted to contain a roll of suitable cleaning material M. The drum 12 may be provided with a removable cover, not shown.

At the upper end of the handle, a plurality of hook members 15 are secured in spaced parallel relation, and each hook member is provided on its inner or concave edge with a cutting portion 15a as best shown in Figs. 2 and 6.

A clamping lever 20 is pivoted at 21 to the upper end of the handle portion 10 and comprises a curved or segmental clamping portion 22 and an end portion 23 (Fig. 4) having teeth or serrations 24 on its lower edge. The clamping lever 20 is of substantially U-shaped section and a slot or opening 27 (Fig. 3) is provided in its outer surface.

The handle portion 10 is preferably U-shaped in cross section, as shown in Fig. 5, and with the longitudinal edge shown uppermost in Fig. 2 open to facilitate insertion and threading of the cleaning material M. The drum 12 is provided with a slot or opening 12a through which the cleaning material M may be drawn out for threading into the handle portion 10.

The preferred cleaning material, as shown in Fig. 6, comprises a relatively narrow strip of fabric 30 and a second and wider strip of fabric 31 which is applied to the

2

fabric 30 in a series of parallel pleats or folds which are stitched to the fabric 30 in a series of parallel lines as indicated at 30.

This material M is threaded through the handle portion 10 to the open upper end thereof, where it is drawn out and forced over the open ends of the curved hook members 15. The advance end of the material is then drawn off over the base of the hooks, and is simultaneously slit longitudinally by the cutting edges 15a. The slitted material is then passed down through and under the clamping lever 20, and with the lower end of the material M projecting therefrom as indicated in Fig. 1. The cleaning device is then ready for its intended use which is carried out by inserting the convex or outer edges of the hook members 15 together with their enclosing pleats between the peripheral portions of a plurality of closely adjacent thin discs such as are commonly used in automatic telephone apparatus.

After the cleaning device has been used until the cleaning material has become worn or soiled, the clamping lever 20 may be swung to the open position indicated in Fig. 2, and the end portion of the cleaning material may then be drawn firmly around the serrated end 23 of the clamping lever 20. When held in that position, as indicated in Fig. 2a, the material M will be firmly engaged by the teeth 24. If the clamping lever 20 is then swung downward to the closed position indicated in Fig. 1, the soiled cleaning material will be drawn downward past the cutting edges 15a, and the slitting operation will be facilitated by the substantial leverage thus applied.

The supply of cleaning material is thus quickly and easily replenished on the hook members 15, and the cleaning device is ready for further use. When the clamping lever 20 is in the position shown in Fig. 1, the clamping portion 22 thereof is effective to prevent displacement of the cleaning material and holds the pleated material M snugly against the concave or inner edges of the hook members 15.

If the device is to be used for lubricating as well as cleaning, the material M may be moistened with a suitable lubricant.

For certain purposes, it may be desirable to use cleaning material M' (Fig. 7) in the form of separate tubular strips, instead of material having the unitary and pleated construction shown in Fig. 6.

Having thus described my invention and the advantages thereof, I do not wish to be limited to the details herein disclosed, otherwise than as set forth in the claims, but what I claim is:

1. A cleaning device for storing and operatively presenting strip cleaning material having a plurality of tubular longitudinal pleats which comprises a handle, a storage device for said cleaning material mounted at one end of said handle, and a plurality of identical parallel spaced and curved supporting hook members each attached by 50 one end portion to the second end of said handle, and the hooked end portions of said members projecting freely from said handle and effective to receive pleats of said strip of cleaning material, said handle having a passage therethrough for transit of said cleaning material to the free outer ends of the hook portions of said hook members, each supporting hook member having a cutting edge portion on its concave inner face adjacent the end thereof which is attached to said handle, and said cutting edge 55 portions severing the strip of cleaning material as said material is drawn through said device and toward said handle.

2. The combination in a cleaning device as set forth in claim 1, in which a clamping lever having a curved end portion is provided, which clamping lever is mounted on said handle for movement of its curved end portion to-

ward and away from the concave inner edges of said hook members to clamp and release said cleaning material.

3. The combination in a cleaning device as set forth in claim 1, in which a lever is pivoted to the handle and overlies a portion of the cleaning material which has been severed by said hook members, and in which said lever has a serrated holding edge at its free end and is effective to draw a portion of said severed strip material off of the base of said hook members as the free end of said lever is swung toward said handle and with a portion of said severed strip material pressed against said serrated edge.
